LABELING MACHINE

Robert John Newman and David Sidney Friend,
London, EnglandApplication April 16, 1951, Serial No. 221,154
In Great Britain January 1, 1951

2 Claims. (Cl. 216—54)

1

This invention relates to labelling machines of the kind having a pair of side gum plates or pickers mounted for reciprocatory movement, e. g. in a horizontal plane, from a position where they are gummed to a position where they receive a label from a stack of labels, and then to a further position where the label is applied to a package or container by means of a plunger, the plunger and/or the package being moved during this operation between the gum plates.

Since the plunger and/or the container moves between the gum plates for the purpose of removing the gummed label from said plates and transferring it to the package or container, the gum plates must be spaced a considerable distance apart. As a result the labels are gummed only over areas which are spaced apart, leaving an ungummed area which in some cases gives rise to a poor appearance of the applied label. The provision of means to overcome this disadvantage has met with certain difficulties such as twisting of the label and it is the principal object of the present invention to provide means by which the labels are gummed over their entire area and in which the difficulties hitherto encountered are eliminated.

According to the invention a labelling machine comprises a central gum plate which fits between the side gum plates, means for bringing a label box against the three gum plates while they are disposed in a common plane, and means for displacing the central gum plate out of said plane while the box is maintained against the side gum plates. The machine is preferably also provided with means whereby the label box is then removed from the side gum plates so as to leave a label on said plates, the latter being then moved to the label applying position while the central gum plate remains at the label box position. The side and central gum plates may thereafter be returned to a position rearwardly of the label box position to receive a new coating of gum, this movement of the central gum plate being effected by the movement of the side gum plates.

The central gum plate may be carried by or made integral with a slide mounted in a guideway in a tiltable member whereby the central gum plate can be displaced slidably in the plane of the side gum plates and further displaced out of that plane by tilting.

An embodiment of the invention is illustrated by way of example in the accompanying drawings, in which:

Figure 1 is a longitudinal sectional view of 55 nions 20 by which it is journalled for pivotal

2

part of a labelling machine showing the gum plates and associated mechanism;

Figure 2 is a plan view of Figure 1 with the cover removed; and

Figure 3 is an end elevation, partly in section, looking in the direction of arrow III in Figure 1.

Referring to the drawings, the numeral 10 designates the rear end wall of a labelling machine which may be of the kind illustrated in

Figures 1 to 14 of our Patent No. 2,513,511, said machine including a pair of laterally spaced side gum plates 11, 12 which are arranged in a horizontal plane and are mounted for movement towards and away from the front of the machine under the action of a cam (not shown) on a cam shaft 13 to which rotational movement is imparted in any convenient manner. The machine also includes a gumming mechanism for applying a coating of gum to the top faces of the gum plates; a label box arranged above the plane of the gum plates and movable vertically into and out of engagement with said plates; and a plunger by which a label which has been picked off from the stack within the label box is pushed down between the gum plates and applied to an article to be labelled. The label box, gumming mechanism and label applying means, none of which is shown in the drawings, may be constructed, located and operated as in our aforesaid Patent No. 2,513,511, the operating cams being arranged on the cam shaft 13 so that the said parts and the gum plates are actuated in synchronism.

In accordance with the present invention and to ensure that each label has a coating of gum applied over its entire surface, a further gum plate 14 is provided which during the operations of gumming the side plates 11, 12 and picking off a label from the label box, is located in the space between, and in the same plane as, said side gum plates, and is thereafter actuated to disengage from the picked off label so that the latter may be moved with the plates 11, 12 to the label applying or transfer position. As illustrated, the gum plate 14 is integral with a slide

15 extending longitudinally through an opening 16 in the rear machine wall 10, said plate being located at the forward end of the slide and of a width corresponding to the spacing between the side gum plates 11, 12. The slide 15 is mounted for longitudinal movement in a guideway 17 provided in the top face of a bracket 18 and is held within said guideway by top plates 19, 19 secured to the bracket. The bracket is provided at its forward end with depending trun-

50 nions 20 by which it is journalled for pivotal

movement on a horizontal transverse spindle 21 mounted in a bracket 21a on the rear wall 10 of the machine. The shaft 21 also has pivoted thereon a two-armed lever, one arm 22 of which extends through an opening 19a in the wall 10 and carries a follower roll 23 running on a cam disc 24 on the cam shaft 13, while the other arm 25 of said lever carries an adjustable stop in the form of a bolt 26 which abuts against the bracket 18. A tension spring 27 connected between a pin 28 on the wall 10 and a further pin 29 on the bracket urges the two-armed lever 22, 25 in a direction such as to hold the roll 23 towards the cam 24, and an adjustable stop bolt 30 mounted in the wall 10 limits such movement of the lever so that when the cam is located with its lowest part facing the roll 23 the central gum plate is positioned horizontally and in the same plane as the side gum plates.

The slide 15 and central gum plate 14 are urged in the forward direction by a pair of tension springs 32 disposed at opposite sides of the slide and connected between a bar 33 secured to the rear end of the slide and plates 34 secured on a bracket 35 integral with the side gum plates or to which said plates are secured. The bracket 35 co-operates with guide rods 36 (only one of which is shown) extending from the rear wall 10 to the front wall 37 of the machine. The slide has fixed thereon a depending abutment 38 which is held by the springs 32 in engagement with a rawhide plug 39 on the rear end of the bracket 35. The slide also has fixed thereon a bracket 40 which at its forward end carries an adjustable stop bolt 41 adapted on forward movement of the slide to abut the wall 10 and thus arrest the slide in a position such that the central gum plate 14 is located beneath the label box. The gummed labels, as will hereinafter be evident, are moved from the label box position to the transfer position by the side gum plates.

At the commencement of a labelling operation the mechanism is in the position shown in the drawings, with the central gum plate 14 located between the side gum plates 11, 12 and in the same horizontal plane as said side plates. As in our aforesaid Patent No. 2,513,511, the label box, gumming mechanism and label transfer or applying plunger are raised. After a package or container to be labelled is placed in position on a cradle adjacent the front wall 37, which cradle may be supported for vertical movement as in our said Patent No. 2,513,511, the side gum plates move forwardly and the gumming roller is lowered to apply to said plates a layer of gum. During this forward travel the abutment 38 is held by the springs 32 in contact with the plug 39, and the slide 15, and consequently the central gum plate, are also moved forward so that said central gum plate also receives a layer of gum from the gumming roller. When the stop bolt 41 abuts the wall 10, as shown in broken lines at 41' in Figure 1, to arrest the slide the gum plates 11, 12 and 14 are located beneath the label box and the side gum plates are also arrested by their actuating cam, the bracket 35 then being in the position shown in broken lines at 35'. The gumming roller is raised to have a new coating of gum applied to its surface and the label box descends into engagement with the side gum plates, whereupon the lowermost label in the box contacts the side and central gum plates and is afterwards withdrawn from the box as the latter returns to its upper position.

During the remaining part of the operation,

which may be identical with that of the machine described in our aforesaid Patent No. 2,513,511 and in which the side gum plates make a further forward movement until the bracket 35 reaches the position shown at 35'' (which corresponds to the label transfer position) and thereafter return to their rearmost position, the central gum plate is retained at the label box position by the stop bolt 41 and its return movement is effected on re-engagement of the plug 39 with the abutment 38. However, before the label box is returned to its upper position and the side gum plates moved forwardly from the label box position it is necessary, in order to prevent damage to the label, to disengage the label from the central gum plate. For this purpose the bracket 18 carrying the slide 15 is rocked in a clockwise direction as seen in Figure 1 by the cam 24 so that the central gum plate is moved downwardly out of the plane of the side gum plates. This frees the central gum plate from the label, which remains attached to the side gum plates until it is removed therefrom at the transfer position of said side plates. The central gum plate is returned to its upper position by rocking movement of the bracket 18 in a counterclockwise direction under control of the cam 24 after the label on the side gum plates has cleared the forward end of said central plate and preferably before the latter commences its rearward movements.

Lubrication of the slide 15 may be effected by means of a pair of oil nipples 43 carried by a casing 44 enclosing the rear end of the slide and the bracket 18, said nipples registering with notches 45 (Figure 2) cut in the inner edges of the plates 19. Oilways 46 may also be provided, as shown in Figure 2, in the slide.

We claim:

1. In a labelling machine having a label box, a pair of side gum plates spaced apart to form a gap between them and mounted for reciprocatory movement in the plane of said plates, means for moving the label box against the gum plates for transferring a label from the label box to the gum plates, gumming means for applying gum to the gum plates at a gumming position and label applying means located at a label applying position spaced from said label box for transferring a label from the gum plates to an article to be gummed, the provision of means for reciprocating said gum plates lengthwise thereof from the gumming position through the label box position to the label applying position, a tiltable carrier mounted on an axis transverse to the direction of reciprocation of said plates, a central gum plate located between said side gum plates and mounted on said carrier slidably lengthwise of said plates, resilient means for advancing said central gum plate slidably on said carrier to maintain the central gum plate in said gap while the side gum plates move from the gumming position to the label box position, means for tilting said carrier to move the central gum plate out of said gap when the label box has applied a label to the plates, a pair of coacting abutments attached to the side gum plates and to the central gum plate respectively, said resilient means urging said abutments into engagement with one another, and a second pair of abutments attached to the central gum plate and to the frame respectively for preventing advance movement of the central gum plate and to the frame respectively for preventing advance movement of the central gum

plate beyond the label box position of the gum plates.

2. In a labelling machine having a label box, a pair of side gum plates spaced apart to form a gap between them and mounted for reciprocatory movement in the plane of said plates, means for moving the label box against the gum plates for transferring a label from the label box to the gum plates, gumming means for applying gum to the gum plates at a gumming position and label applying means located at a label applying position spaced from said label box for transferring a label from the gum plates to an article to be gummed, the provision of means for reciprocating said gum plates lengthwise thereof from the gumming position through the label box position to the label applying position, a tiltable carrier mounted on an axis transverse to the direction of reciprocation of said plates, a central gum plate located between said side gum plates and mounted on said carrier slidably lengthwise of said plates, resilient means for advancing said central gum plate slidably on said carrier to maintain the central gum plate in said gap while the side gum plates move from the gumming position to the label box position, the gum plates being on one

side of the axis on which the carrier tilts and the carrier extending on the other side of said axis, a cam actuated lever which engages the carrier to move it upwards about said axis thereby tilting the central gum plate downwards to move the central gum plate out of said gap when the label box has applied a label to the plates, a spring which urges the carrier and lever downwardly about said axis, an adjustable stop which is engaged by said lever to limit the movement of the carrier and lever when the central gum plate reaches the plane of the side gum plates, and means for preventing further advance movement of the central gum plate slidably on said carrier when the side gum plates move from the label box position to the label applying position.
